ELECTRICAL SWITCH ENCLOSURE

Joseph J. Gribble, Fox Point, and Kenneth J. Marien,
Milwaukee, Wis., assignors to Square D Company,
Detroit, Mich., a corporation of Michigan

Application July 31, 1958, Serial No. 51,997

Term of patent 14 years

(Cl. D26—13)

FIG. 1

FIG. 2

FIG. 3

Fig. 1 is a front perspective view of an electrical switch enclosure showing our new design.

Fig. 2 is a side elevational view; and

Fig. 3 is an end elevational view thereof, wherein the broken line showing of legible matter in the drawing is for illustrative purposes only.

The dominant features of our new design are shown in solid lines in the drawing.

We claim:

The ornamental design for an electrical switch enclosure, substantially as shown and described.
